Specification for Design.

Patented Jan. 17, 1922.

Application filed April 30, 1921. Serial No. 465,842. Term of patent 14 years.

To all whom it may concern:

Be it known that I, CHARLES E. MULLINS, a citizen of the United States, having residence at Roanoke, in the county of Woodford and the State of Illinois, have invented a new, original, and ornamental Design for a Building Tile, of which the following is a specification, reference being had to the accompanying drawings, forming a part thereof.

The drawing is a perspective view of a building tile embodying this design.

I claim:

The ornamental design for a building tile, as shown.

In testimony whereof, I have hereunto set my hand at Roanoke, Ill., this 26th day of April, 1921.

CHARLES E. MULLINS.
